WEB SCREEN PRINTING MACHINE
Guilford B. Melton, Gaffney, S.C., assignor to Southern
Powell Corporation, Cherokee Finishing Company Di-
vision, Gaffney, S.C., a corporation of Delaware
Filed Sept. 2, 1964, Ser. No. 393,898
1 Claim. (Cl. 101—123)

The present invention relates generally to a screen printing machine in which a fabric or other article to be printed is passed on a conveyor under a screen carried by the machine and the screen is vertically movable into and out of engagement with the fabric between successive steps of movement of the fabric on the conveyor.

Presently in use are screen printing machines having 15 silk screens through which ink is pressed by a conventional scraper moving back and forth on a tie rod, the silk screen being carried by a frame and suspended from the tie rod for movement with the tie rod into and out of engagement with the fabric to be printed.

Due to the thinness of the silk carried by the frame the silk screen is subject to damage if not carefully handled in its movement into and out of engagement with the fabric to be printed. Also, because the ink which has been pushed through the screen and printed on the fabric causes the screen to adhere to the fabric it is advantageous to be able to lift up one end or the other end of the screen as desired in order to free the screen from the fabric without damage to the screen. Machines presently in use are constructed so that one end of the screen is repeatedly raised before the other end is raised or both ends are raised simultaneously.

An object therefore of the present invention is to provide a mechanism in connection with a screen printing machine which, at the will of the operator, permits raising of the screen at either end first and then the other or both ends simultaneously.

Another object of the present invention is to provide a new and improved means of moving the scraper mechanism in both directions on the tie rods over the screen, such improved mechanism providing a wide range of variable speed of the machine in its printing cycle.

A further object of the present invention is to provide a screen printing machine of new construction, one simple in structure, one easily constructed and assembled, one which is highly efficient in action, and one which is economically feasible.

These and other objects and advantages of the present invention will be apparent from a consideration of the following description when taken in the light of the appended drawings in which:

FIGURE 1 is a top plan view of the machine according to the present invention.

FIGURE 2 is an elevational view of the machine as seen longitudinally of the conveyor on which the fabric travels,

FIGURE 3 is a front end view of the machine transversely of the conveyor,

FIGURE 4 is a rear end view,

FIGURE 5 is a fragmentary view of a portion of the machine as seen in FIGURE 2, on an enlarged scale and with parts broken away,

FIGURE 6 is a view taken on line 6—6 of FIGURE 5, on an enlarged scale,

FIGURE 7 is a fragmentary elevational view of a portion of the machine, and

FIGURE 8 is a view taken on the line 8—8 of FIGURE 5.

Referring in greater detail to the drawings in which like numerals indicate like parts throughout the several views, the machine of the present invention includes a bed having columns 12 along one side at each end thereof and

2

columns 14 along the other side at each end thereof with a rail 16 on the upper ends of each pair of columns 12 and 14 as shown most clearly in FIGURE 3.

Along the rails 16 is rollably supported a carriage 18 having a front end 20 and a rearward end 22 as shown in FIGURES 1 and 2.

10 Mounted on the carriage 18 for upward and downward movement are laterally spaced apart tie rods 24 and 26 arranged horizontally and carrying thereon across member 28 from which depends a scraping mechanism 30 including blades 32.

The cross member 28 is driven longitudinally of the tie rods 24 and 26 by means of a chain drive 34 running over sprockets 36 and 38 at the front end and rear end of the carriage, respectively. The sprocket 36 is mounted upon a motor shaft 40 rotated by an hydraulic motor 42 which is carried by the carriage 18.

20 The sprocket 38 is carried on a transversely arranged shaft 44 supported at its ends in trunnions 46 depending from the tie rods 24 and 26.

Suitable automatic controls are provided but are not shown here for automatically reversing the travel movement of the cross member 28 when it reaches one end of the printing frame 48 depending from and supported 25 by the brackets 50 mounted on the tie rods 24 and 26.

A conventional screen is mounted in the printing frame 48 and the blades 32 are used to press ink or other printing material through the interstices of the screen to apply the ink or other printing material to a fabric carried on 30 the bed of a conveyor designated generally by the reference numeral 51 in FIGURES 1 and 2.

The hydraulic motor 42 provides a means for driving the cross member 28 which is new and important in the printing industry. Previously electric motors have been used with but a single speed. The hydraulic drive of the present invention provides a variable speed for the cross member permitting a faster cycle of operation than the electric motor drive and also a slower cycle of operation when desired.

40 The invention also provides a novel means for lifting the frame from the fabric or material being printed by lifting either one or the other ends of the frame or by lifting the both ends simultaneously at the will of the operator.

45 This means includes an hydraulic or pneumatic cylinder 52 having its piston rod 54 connected to one end of a swinging arm 56 which has its other end fixedly secured to a gear 58, the gear 58 being mounted upon a short shaft 60 journaled in uprights 62 rising from the rear end 22 of the carriage 18 as shown most clearly in FIGURE 4.

An identical mechanism, as shown in FIGURE 3, is mounted on the front end 20 of the carriage 18.

50 Shafts 64 at each end of the carriage 18 are journaled for rotation in trunnions 66 and a gear carried on the mid portion of the shaft 64, as at 68, is meshingly engaged with the gear 58.

A cam 70 is carried on each end of each of the shafts 64 for rotation therewith and is supportingly engaged 60 with the tie rods 24 and 26 for raising and lowering the tie rods 24 and 26 as a result of its rotation, the cams 70 also bearing upon adjacent portions of the carriage 18 as shown most clearly in FIGURE 5 with reference to the rearward end 20 of the carriage 18.

65 It will be seen therefore that upon the admission of hydraulic fluid or air under pressure into the hydraulic or pneumatic cylinder 52 the pistons 54 will be extended and the arm 56 swung upwardly so that the gears 58 and 68 rotate to rotate the cam 70 which affects the upward movement of the tie rods 24 and 26 at either end of the carriage 18 with the cylinder 52 actuated simultaneously or independently of each other as desired.

Each of the blades 32 is provided with an adjusting device for raising the blade into and out of engagement with the screen, as shown in FIGURES 6 and 7. This means includes studs 72 having brackets 74 on their lower ends with lock nuts 76 positioning the studs 72 at the proper height according to the blade 32 and its engagement with the screen. 5

Brackets 78 carry the studs 72 and are themselves dependently carried from the cross member 28 as shown in FIGURE 5.

A tilting mechanism, indicated generally by the reference numeral 80 brings one or the other of the blades into contact with the screen depending upon the direction of travel of the cross member 28 in the conventional manner for which no invention is claimed.

The printing frame 48 is received at each end on an S-shaped plate 82 carried by the adjacent bracket 50 with pins 84 projecting upwardly from the plate 82 and received in holes provided in the adjacent portion of the printing frame 48.

Lateral adjustment of the printing frame is made possible by a chain and gear drive designated generally by the reference numeral 86 in FIGURE 8, this being necessary so that proper register of the screen can be made with reference to the printing done by a previous screen 25 on the fabric or article to be printed.

The cams 70 work against compression spring and rod assemblies 71 and 73, at the forward and rearward ends of the carriage 18, respectively. Such spring suspension assemblies 71 and 73 are conventional and serve to resiliently support the printing frame and screen on the fabric or surface to be printed. The cams 70 first relieve the compression in the spring assemblies as they rotate to lift the frame upwardly to the position freeing the screen 30 from the printed fabric.

The invention also includes, at the forward end of the carriage 18, means for adjustably limiting the downward travel of the frame. This means consists in adjustable and tapered plugs 75 receivable in matching sockets 77 upon execution of downward movement of the frame, insuring exact positioning and registry of the frame and screen upon the fabric to be printed.

In use, the carriage 18 may be shifted along the rail 16 and locked in place by a hand set screw 88 in FIGURE 5 so that more than one carriage 18 may be employed upon the rails 16 and bed 10, thus permitting several screens to be used simultaneously or in successive steps on one piece of fabric as it travels over the conveyor 51.

After each successive printing of one screen, the tie rods 24 and 26 are raised either at both ends simultaneously or one end first and then the other so that the screen is lifted from the fabric being printed. Downward movement of the tie rods 24 and 26 takes place as a result of gravity and the forces of spring and rod assemblies 71, 73 when the cam is rotated to its original position.

While only a preferred embodiment of the present invention is shown, other embodiments are contemplated and numerous changes and modifications may be made in the invention without departing from the spirit thereof as set forth in the appended claim.

What is claimed is:

A screen printing machine comprising:
a pair of parallel tie rods extending longitudinally 60 from a first end to a second end of the machine;

a carriage slidably mounted for reciprocable movement on the tie rods, said carriage comprising, a transverse beam, the ends of said beam being slidably mounted on the tie rods, a pair of downwardly extending brackets proximate the ends of the beam, a pair of relatively angularly disposed squeegee blades secured parallel to the transverse beam by the brackets, and means for adjusting the position of the blades relative to the transverse beam; an endless chain secured at one point to the carriage; a pair of sprockets disposed at opposite ends of the machine for supporting the endless chain; drive means connected to the sprockets for reciprocably moving the carriage on the tie rods; a plurality of brackets mounted on the tie rods and extending downwardly therefrom for supporting a printing frame; a screen printing frame secured to said brackets, said printing frame being disposed below and adjacent the squeegee blades; first and second end carriages; means securing the respective ends of the tie rods to the first and second end carriages for supporting said tie rods; a plurality of wheels on said end carriages; first and second rails disposed transversely of the machine proximate the ends thereof, said rails rollably supporting the first and second end carriages; means biasing the respective ends of the tie rods downwardly toward the respective end carriages; a transverse rod rotatably mounted on each end carriage; cams on both ends of each transverse rod, said cams being positioned for lifting engagement with the means securing the ends of the tie rods to said end carriages for lifting the tie rods relative to the respective carriage when the transverse rod is rotated; a first gear secured intermediate the ends of each transverse rod; a second gear engaged with each first gear; a swinging arm secured to each second gear; and a linear fluid motor secured to each swinging arm for independently rotating each second gear for rotatably driving each transverse rod independently to lift the respective ends of the tie rods independently of the other ends of the tie rods.
